UNITED STATES PATENT OFFICE.

VERN E. REICHARD, OF PERRY, NEW YORK.

COLLAPSIBLE BOX.

1,308,865.

Specification of Letters Patent.

Patented July 8, 1919.

Application filed April 8, 1918. Serial No. 227,345.

To all whom it may concern:

Be it known that I, VERN E. REICHARD, a citizen of the United States, residing at Perry, in the county of Wyoming and State of New York, have invented certain new and useful Improvements in Collapsible Boxes, of which the following is a specification, reference being had to the accompanying drawings.

This invention relates to certain improvements in collapsible boxes and has relation more particularly to a device of this general character including a plurality of hingedly connected sections or panels which, when in folded relation, occupy a minimum of space, and it is an object of the invention to provide a device of this general character with novel and improved means whereby the sections or panels may be maintained in extended or operative relation.

The invention consists in the details of construction and in the combination and arrangement of the several parts of my improved collapsible box whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation of a collapsible box constructed in accordance with an embodiment of my invention, in extended or operative position;

Fig. 2 is a transverse sectional view taken through my improved box as disclosed in Fig. 1;

Fig. 3 is a transverse sectional view taken through my improved box in folded or collapsed position;

Fig. 4 is a longitudinal vertical sectional view taken through my improved box as herein disclosed in extended or operative position; and

Fig. 5 is a longitudinal vertical sectional view taken through my improved box as herein disclosed in folded or compacted position.

As disclosed in the accompanying drawings B denotes the bottom panel of my im-

proved box which is preferably rectangular in form and has its longitudinal marginal portions defined by the upstanding flanges 1. Hingedly connected to the flanges 1 are the side panels S which are adapted to fold inwardly. It is to be observed that the hinges 2 are so positioned as to cause the adjacent edges of the flanges 1 and the panels S to contact in order to limit the outward swinging movement of the panels S.

E denotes end panels hingedly connected with the bottom panel B and adapted to fold inwardly and upon the inner face of the panel B. The flanges 1 are of a width in excess of the thickness of the panels E so that when my improved box is collapsed the end panels E will offer no obstruction to the inward or folding movement of the side panels S. The hinges 2 connecting the bottom panel B and the end panels E are so arranged that the upward swinging movement of the panels E is limited by contact of the inner edges thereof with the bottom panel B.

Each of the end panels E is provided with inward guide members 3 alined in a direction transversely of the bottom panel B and slidably engaged with said guide members 3 are the rods 4 having their outer ends provided with the hook members 5 engageable with the eye members 6 extending inwardly from the side panels S. Coacting with the inner end portions of the rods 4 is a turnbuckle 7 or the like whereby the requisite pull may be imparted to the rods 4 for maintaining the panels S and E in extended or operative relation and which also permits a ready release of such panels when it is desired to compact the box.

The outer face of each of the end panels E has its marginal portions defined by the outstanding members or flanges 8 and the uppermost of said flanges or members 8 is provided to one side of its longitudinal center with an opening 9 extending in a direction substantially parallel to the outer face of the panel E. Disposed through said opening 9 is a shank 10 having its inner portion anchored as at 11 to the panel E and its opposite end portion extending beyond the outer margin of the panel E. Hingedly connected as at 12 with the outer longitudinal margin of the side panels S are the top panels T, which are adapted to be swung over and in contact with the upper

or outer marginal portions of the panels S and E when the box is extended or in assembled relation and which panels T are adapted to overlie the outer faces of the panels S when the box is folded or compacted. As herein embodied the top panels T are each of a width substantially equal to one-half of the width of the bottom panel B. One of the panels T adjacent its opposite ends is provided with the openings 14 through which the extended portions of the shank 11 is directed when the panel T is in closed position and the second panel T adjacent its opposite ends is provided with a strap 15 extending beyond the outer or free longitudinal margin thereof and the extended portions of said straps are provided with the openings 16 through which the extended or outer end portions of the shanks 11 are also disposed when both of the panels T are in closed position. As is clearly illustrated in the accompanying drawings, the extended portions of the straps 15 overlie the outer face of the second panel T when the panels are in closed position. The nuts 17 are threaded upon the shanks 11 and have clamping engagements upon the straps 15 or more particularly the extended portions thereof whereby the top panels T are effectively and conveniently locked in closed position.

From the foregoing description, it is thought to be obvious that a collapsible box constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying

out my invention in practice except as hereinafter claimed.

I claim:

1. In combination with a box body having a face open, the outer faces of opposed walls of the body having their free marginal portions defined by outstanding flanges, a cover panel coacting with the open face of the body, said panel being provided with openings adjacent opposite ends thereof, outstanding shanks carried by the body and disposed through the flanges thereof, the inner ends of said shanks being secured to the outer faces of the walls provided with the flanges, the outer end portions of said shanks being insertible through the openings in the cover panel, and clamp members threaded upon the shank and coacting with the cover panel for holding the same in closed position.

2. A collapsible box comprising a bottom panel, side panels and end panels, foldable one relative to the other, an inwardly directed eye carried by each of the said panels adjacent an end thereof, a rod slidably supported by an end panel and provided with a hook engageable with the eye of a side panel, a second rod in longitudinal alignment with the first named rod and having a hook engageable with the eye of the second side panel, and a member engageable with the inner ends of the rods for imparting pull thereto for holding the end panel and the side panels in extended relation, said member also serving as means whereby the second rod is supported by the first named rod, both of said rods having movement in substantially a fixed line of travel.

In testimony whereof I hereunto affix my signature in the presence of two witnesses.

VERN E. REICHARD.

Witnesses:

E. ALICE SMITH,
ARTHUR E. MILLER.
